UNITED STATES PATENT OFFICE.

ROBERT A. HAMMOND, OF SANDWICH, MASSACHUSETTS.

WOVEN FABRIC.

No. 926,868.

Specification of Letters Patent.

Patented July 6, 1909.

Application filed September 5, 1908. Serial No. 451,866.

To all whom it may concern:

Be it known that I, ROBERT A. HAMMOND, a citizen of the United States, residing at Sandwich, in the county of Barnstable and 5 State of Massachusetts, have invented a new and useful Woven Fabric, of which the following is a specification.

In woven fabrics adapted for use as tension devices, such as ropes for hoists or belts 10 for the transmission of power, and particularly where these are to be subjected to moisture, a very useful organization is that described in the patent to Kast, No. 841,154 of January 15, 1907, in which a series of 15 parallel, longitudinal strands, each composed of a plurality of wires twisted together and served with marline, are united by similar transverse strands interwoven with them. Such devices possess well recognized merits with regard to strength, durability, and frictional transmitting capacity, 20 but also have certain disadvantages. For example, the patentee's wires making up each strand, because of their twist, incur a 25 compound bending action across their companions which is liable to result in their breakage; the roughness of the twisted surface to some extent cuts the covering; and the sharply rounded surface of the longitudinal strands produces intermediate depressions which decrease the effective frictional 30 surface.

The object of the present invention is to overcome these difficulties, and to provide a 35 still more durable and efficient device.

In the accompanying drawing forming a part of this specification, Figure 1 is a front elevation of a portion of one embodiment of my invention; Fig. 2 is a longitudinal section therethrough on the line 2—2 Fig. 1; and Fig. 3 is an enlarged transverse section on the line 3—3 of Fig. 1.

Similar characters are applied to like parts in the several figures of the drawing. 45 The letter A designates a member extending longitudinally of my improved tension device, and consisting of a central portion or core 10 and a covering 11. The core is preferably provided by a flat wire, of any de- 50 sired metal, and which is in section of the general form of a parallelogram; that is, having opposite parallel plane surfaces 10^a—10^a and symmetrically disposed ends 10^b—10^b, which are, however, slightly curved so that 55 they merge gradually into the plane surfaces. One dimension of this section, that between

the curved ends, is greater than any other transverse dimension of the wire. The covering 11 may be of any suitable yieldable material, but is preferably of a fibrous character 60 and waterproof. Marline wound closely over the wire is excellent for this purpose. The longitudinal strands A are arranged in a series side by side, usually in a single layer, with their maximum dimensions or diameters lying in the same plane across the width of the device, and with the curved surfaces of adjacent strands in proximity to one another. 65

The strands A are maintained in their correct relation to form a flat rope or belt, by 70 transverse members or strands B interwoven with them, and each conveniently consisting of a core 12 of a single round wire, having a covering 13 of the same material as the longitudinal strands. The manner in which I 75 prefer to weave together or connect the members is clearly shown in the drawing, where it will be seen that there are two of the transverse strands crossing the device in opposite directions, and passing upon opposite 80 sides of successive strands A. In the crossing the strands B parallel one another, with their intersections at the outside of the device adjacent to the outer members A. The retaining strands are thus protected from 85 wear by the longitudinal strands, the latter wholly furnishing the working or friction surface. Moreover, the intersection of the cross strands at the edge of the device adds to its thickness only that of a single strand, 90 and these cross strands are not forced against and do not wear one another.

Obviously, the device presents a large portion of its total area for contact with a pulley or like member, for not only do the flat wires 95 furnish considerable uninterrupted friction surface transversely of the device, but the space between their curved edges is so slight that in use it is so filled by the covering that the surface is practically continuous. In 100 neither set of strands are there sharp projections to cut the covering, and the fact that each strand contains but one wire, bending always in the same direction over a pulley, 105 reduces the tendency of the metal to crystallize and rupture. In addition to the advantages above pointed out, my improved tension device possesses all the ordinary desirable features of ropes and belts of this class.

I claim:

1. A fabric adapted for use as a rope or

belt for the transmission of power and like purposes comprising longitudinal strands of wire having flat working faces, transverse retaining wire strands interwoven with the 5 longitudinal strands and crossing the flat faces thereof, and a covering of yieldable material enveloping each of the strands.

2. A fabric adapted for use as a rope or belt for the transmission of power and like 10 purposes comprising longitudinal strands of wire having flat working faces of greater width than the thickness of the wire, interwoven transverse retaining strands, and a covering of yieldable material enveloping 15 each of the strands.

3. A flat rope or belt comprising longitudinal strands having flat working faces and curved edges adjacent to one another in successive strands, interwoven retaining strands

crossing said flat faces and passing between 20 the curved edges, and a covering of yieldable material enveloping each of the strands.

4. A fabric adapted for use as a rope or belt for the transmission of power and like purposes comprising longitudinal strands of 25 wire having flat working faces, and transverse retaining strands interwoven with the longitudinal strands, all the strands of the fabric presenting a surface of yieldable material for contact with the associated strands. 30

Signed at Boston, in the county of Suffolk and State of Massachusetts, this third day of September, 1908.

ROBERT A. HAMMOND.
